ABSTRACT OF THE DISCLOSURE

An apparatus for logging is provided using an autogiro and having powered winch means at a log dump area connected to the autogiro by a line for pulling the autogiro with a load of logs from a cutting area. The autogiro has means for lifting a log load under its own power at the cutting area and is capable of being pulled rearward to the log dump area under power of the winch whereby it is substantially maintained in flight by pulling forces imparted by the winch. The autogiro returns with the line to the cutting area under its own power. For the above purpose, the autogiro has rotor blades driven by jets on the ends of the blades to accomplish the load lifting function and has a propeller to drive it in its return movement. The aircraft also has air pickup means to utilize forced air from the propeller to assist in driving the rotor. The rotor blades of the autogiro have a resilient cushion connection with the aircraft to permit the blades to pivot a short distance forward or rearward or up or down. Arms are connected between adjacent rotor blades to anchor the latter against rotation on their longitudinal axes.

This application is a continuation-in-part of application Ser. No. 570,955, filed Aug. 8, 1966, now abandoned, by William H. Rock, for Method and Apparatus for Aircraft Logging.

This invention relates to a new and novel apparatus for autogiro logging.

A primary objective of the present invention is to provide an apparatus which utilizes an autogiro for lifting a log or tree vertically from a logging site or pile and transporting the same with the assistance of power winch means to a selected site such as a log dump.

A more particular object is to provide a novel combination of structure wherein an autogiro is adapted to have movement to and from a logging site with the assistance of power winch means, for accomplishing a logging operation.

Another object is to provide autogiro structure which has rotor means together with novel drive means for the rotor, such drive means comprising jet motors at the outer ends of the rotor together with an auxiliary drive for the rotor comprising air pickup means from a propeller on the aircraft.

Yet another object is to provide an autogiro having a novel supporting connection of its rotors wherein said rotors have universal self adjusting movement.

Additional objects and advantages will become apparent from the following description taken in connection with the accompanying drawings which illustrate a preferred form of the device.

In the drawings:

FIGURE 1 is an elevational view of a logging operation employing the apparatus of the present invention;

FIGURE 2 is a top plan view of autogiro structure utilized in the present system of logging;

FIGURE 3 is an enlarged fragmentary sectional view

2

taken on the line 3—3 of FIGURE 2 and showing details of the autogiro rotor;

FIGURE 4 is an elevational view of structure shown in FIGURE 3 with a portion thereof in section;

FIGURE 5 is a cross sectional view of rotor structure taken on the line 5—5 of FIGURE 3; and

FIGURE 6 is an enlarged, fragmentary plan view also of rotor structure.

Referring now in detail to the drawings and first to FIGURE 1, the present logging system has its novelty primarily in the combination of a conventional winch 10 and an autogiro 12. The winch 10 has the usual power plant 14 and a winch drum 16 for hauling in and letting out a line 18, and for the present purpose is readily portable from place to place.

The autogiro 12 has a fuselage 17 supporting both a conventional propeller 20 for driving the autogiro horizontally and a rotor 22 providing vertical lift therefor. The autogiro has a lifting line 24 connected to a winch 26 therein, and the lifting line has a choker assembly 28 for releasable attachment to logs 30.

In a system of logging it is desired to move logs 30 from a pickup or growing site 32 to an unloading or dump site 34, these two sites generally being spaced a substantial distance apart and obviously separated by wooded and rough terrain. By means of the present invention, logs 30 are transported from the pickup site 32 to the unloading site 34.

In the method of logging, the autogiro first pulls the line 18 from the winch 16 at the unloading site 34 to the pickup site 32, such being accomplished by a combination of lifting and pulling power from the rotor 22, as will be explained in greater detail hereinafter, and the propeller 20. With the autogiro hovering over the logging site, the lifting line 24 is lowered and a log connected thereto. Thereupon, the winch 26 is operated to remove slack to the log and at the same time power to the rotor 22 is increased to lift the autogiro and log. The propeller 20 at this time is inoperative since its primary function is to move the autogiro and pull line 18 from the unloading site to the logging site. Once the log has been raised above the treetops, the autogiro is returned to the unloading site 34 as will now be more fully described.

Movement of the autogiro and load from a pickup site 32 to an unloading site 34 is accomplished primarily by intake of line 18 on the winch drum 16. That is, when the autogiro has lifted a log 30 clear of the standing trees, the line 18 is hauled in to fly the autogiro backwards to the unloading site. In this regard, it is desired that the winch 16 have a sufficient pull-in speed for the line 18 such that line 18 serves as a reverse propeller to pull the autogiro rearwardly, and upon developing sufficient haul-in speed some or all of the jet power to the rotor 22, to be described can be turned off. As the speed of the haul-in line 18 is reduced, namely as the autogiro approaches the unloading site 34, it will be necessary to increase the power to the rotor 22 to maintain the autogiro airborne. The log is then lowered to the unloading site 34 and released from the lifting line 24 by suitable trip means associated with the choker assembly 28, whereupon the autogiro with line 18 can then be flown to the logging site under the power of propeller 20 with the rotor 22 being operated by minimum power or none at all after the autogiro has started moving. The autogiro is operated by a pilot therein, and this pilot is in communication, as by radio, with the winch operator and others on the ground as necessary.

By means of the present system of logging, logs are lifted directly upwardly and are not dragged along the ground as in conventional logging. Thus, the valuable ground cover such as small trees, underbrush, moss, root fiber, and animals are not destroyed or disturbed.

Further details of the autogiro which contribute to the desired operation thereof will now be described. Such an autogiro includes an upright housing 36, FIGURES 3 and 4, having a top aperture 37 through which projects a hollow rotor supporting post 38. This post has journaled support in the housing 36 by upper and lower bearings 40. Upper bearings 40 comprises a cup-like bracket 40a secured to the post 38 interiorly of the housing 36 a short distance below the top of the housing. This bracket forms a seat for a resilient insert 40b abutted against the lower surface of the top of the housing and providing a journaled engagement of the upper end of the post 38 and the housing 36, it being understood that the insert 40b is constructed of a friction free material such as nylon or the like. The resilience of the insert 40b may be the result of the resilience of the material itself or as shown the insert may be hollow to provide an air cushion. The insert normally maintains the post centered in the aperture 37 but due to its resilience will permit tilting of said post.

Lower bearing 40 is of any suitable conventional construction and is secured in a clamp bracket 41 at the lower end of the post. Attached to the bracket 41 is a push-pull rod 42 connected to operating means, not shown, which may comprise a fluid operated cylinder for example. By means of the push-pull rod 42, the post 38 may be tilted forwardly or rearwardly, as designated by the arrow 44 in FIGURE 4, and it is to be understood that similar tilting means, not shown, may also be attached to the clamp bracket for tilting the post sideways.

The upper end of rotor supporting post 38 has four equally spaced lateral extensions 46 for supporting the rotor blades 22a. The rotor blades 22a are hollow in construction and preferably are oval-shaped in cross section as shown in FIGURE 5. The ends of the blades 22a which are connected to the lateral extensions 46 have end walls 48 provided with apertures 50 for receiving an end portion of said extensions. Supported on the end portions of the extensions 46 which project into the rotor blades and confined between end walls 48 and flanged end portions 56 of the extensions 46 are resilient cushions 54. Cushions 54 may be solid in construction, or as shown, may comprise air-filled cushions. They provide resilient attachment of the rotor blades 22a to the post 38 or more particularly they permit the blades to pivot a short distance forward or rearwardly or up or down, as is desired for rotor blades in a rotor-type autogiro.

The lateral extensions 46 preferably are oval-shaped, FIGURE 5, to conform substantially to the shape of the base of the rotor blades 22a, and therefore the resilient cushions 54 also assume an oval shape to fit suitably between these two members. It is to be understood that the cross sectional shape of the lateral extensions 46 may be round rather than oval-shaped as shown if the shape of the rotor blades warrant such.

The principal driving power for the rotor comprises jet engines 60 mounted at the ends of the rotor blades. These jet engines are of conventional construction and fuel therefor is fed through lines 62, FIGURES 3 and 4, leading upwardly through the hollow rotor supporting post 38 and extending through the lateral extensions 46 and the hollow rotor blades 22a. Fuel lines 62 lead from a suitable fuel tank, not shown, in the autogiro. Jet engines 60 provide thrust in the direction of arrows 63, FIGURE 2, to rotate the rotor in the direction of arrow 63a, such driven direction of rotation being the same as the autorotative direction of rotation. In other words, the rotor always turns in the same direction regardless of whether the autogiro is traveling forward or reverse. The rotor will also turn in the same direction when the autogiro moves up or down.

Since the connection of the rotor blades 22a on the lateral extensions 46 would permit rotation of the blades

thereon, arms 76, FIGURES 2 and 6, are provided between the blades to prevent such rotation. These arms are connected at one of their ends to a blade, by means of a yoke 78 on the arm and pins 80 on the blades pivotally receiving the yoke, and at their other end to a trailing blade by means of a slidable connection in a socket 82 provided in a projection 84. As seen, an arm 76 extends from each rotor blade for slidable connection in a respective socket 82. Arms 76 serve to anchor the rotor blades against free rotation on the extensions 46 but in view of the pivotal connection on the pins 80 on the one blade as well as the slidable connection in the socket on the following blade, the blades can pivot forwardly or rearwardly a small amount, with relation to the direction of rotation of the rotor, independent of adjacent blades. The blades can also tilt up and down a small amount but will have no appreciable effect on the operation of adjacent blades.

As a part of the present invention, it is also desired to utilize airflow from the propeller 20 to assist in driving the rotor of the autogiro. For this purpose, the sides of the fuselage 17 are provided with scoops 64 for catching air from the propeller and directing such air to the rotors. More particularly, conduits 66, FIGURES 3 and 4, lead from the air scoops 64 to the interior of rotor supporting post 38, and air which is forced through the conduits is adapted to be discharged through nozzles 68, FIGURE 2, adjacent the tip ends of the rotor blades. These nozzles are directed rearwardly whereby air forcefully discharged therefrom will produce forward rotation of the rotor. The connection of the conduit 66 with the rotor supporting post 38 is best shown in FIGURE 3. In such connection, the conduit 66 is integrated with a circular housing 70 which is apertured to rotatably receive the post 38 and which encloses apertures 72 in said post. Housing 70 has a rotatable connection with the post 38 by means of a pair of annular flanges 73 secured to said post and rotatably engaged by the housing in a substantially air-tight fit. Thus, air forced through the conduit 66 is transferred into the post 38 and such air moves outwardly into the rotor blades, as indicated by the arrows 74, and thence to the nozzles 68.

Thus, in the operation of the autogiro for the movement of logs, the jet engines 60 are utilized for the principal lifting power, but at certain times, the trapped air entering the air scoops 64 will serve to assist in driving the rotor.

In accordance with the invention a new system of logging is employed, with the autogiro structure described and illustrated functioning as preferred structure for carrying out the said system of logging. That is, the use of a propeller 20 serves to return the autogiro and line 18 rapidly from the unloading area 34 to the loading area 32. Also, the structure of the rotor blades 22a FIGURE 5, which comprise autogiro blades, produces great lifting power for the autogiro as it is being pulled rearwardly by the cable 18. The autogiro blades are driven by the jets 60 on the ends thereof as necessary, and not by a power plant within the plane. By this structure, the characteristics of an autogiro are maintained since no turning or twisting forces are applied to the body of the aircraft when power is applied by the jets, as distinguished from helicopters. Similarly, the blades are capable of turning freely when the power is off, again without reaction to the body of the autogiro. The autogiro can be pulled forwardly by the propeller and can be pulled rearwardly by the line 18, the operation of the autogiro being identical in either direction in that the rotor operates in the same direction whether the autogiro moves in said forward or rearward directions. Thus, when the autogiro is pulled rearwardly by the line 18, it will remain airborne, assuming of course that the line 18 is hauled in with sufficient speed to keep the autogiro airborne with its load.

A logging operation can be accomplished effectively for a considerable radius around a central area, and such

operation can be carried out over substantially any type of terrain. Also, logs can be removed without any substantial disturbance to the ground cover. The power plant and its fuel, namely, the winch 10 and its fuel, for pulling the autogiro back to the log dump are on the ground and not in the autogiro. In such arrangement winch 10 and its fuel supply do not consume any of the lift of the autogiro, thus allowing greater load to be carried by said autogiro.

It may be necessary to tilt the post 38 in order that the blades 22a will achieve the proper angle in reverse. Such tilting function is accomplished by the push-pull rod 42.

It is to be understood that the form of my invention herein shown and described is to be taken as a preferred example for carrying out the same and that various changes in the shape, size and arrangement of parts may be resorted to without departing from the spirit of my invention or the scope of the subjoined claims. For example, the invention may be carried out in steps wherein more than one pair of loading and unloading sites are employed. That is, if the distance between the loading and unloading sites is too far for the feasible operation of the winch 10 and line 18, more than one set of loading and unloading sites and winches 10 may be employed and the logs transferred step by step from the woods to the final point of loading. Also, it is to be understood that the autogiro apparatus may have a double rotor for greater lifting power. Furthermore, the line 18 may be connected to points adjacent the rearward end of the autogiro other than shown on the drawings.

Having thus described my invention, I claim:

1. Apparatus for moving logs from a cutting area to a log dump area comprising:
  - (a) an aircraft having a fuselage with forward and rearward ends,
  - (b) means suspended from said aircraft for connection to a load of logs,
  - (c) autogiro blades on said aircraft rotatable on a vertical axis and arranged to lift the aircraft and a log load vertically at the cutting area and also arranged to be autorotative to substantially maintain the aircraft and load airborne without power when the aircraft is pulled longitudinally at a selected speed,
  - (d) power drive means on said autogiro blades for rotating the same,
  - (e) propeller means on said aircraft for propelling said aircraft forwardly,
  - (f) power drive means for rotating said propeller means,
  - (g) a line connected at one of its ends to the rearward end of said aircraft,
  - (h) and powered winch means connected to the other end of the line and arranged to be anchored in a fixed position on the ground,
  - (i) said winch means being arranged to pull the loaded aircraft rearwardly through the air from the cutting area to the log dump area at a speed such that the autogiro blades will maintain the aircraft airborne with substantially no power from the power drive means on the rotor blades and propeller,
  - (j) said aircraft being arranged under its own power to return from the log dump area to the cutting area while pulling out the line from said winch means.
2. The logging apparatus of claim 1 wherein
  - (a) said aircraft has an upstanding post for said rotor blades with a lateral extension for each of said blades,
  - (b) one end of said rotor blades being hollow and receiving in overlapping connecting relation respective ones of said lateral extensions,
  - (c) vertical shoulder means on the ends of each of the overlapping ends of said lateral extensions and said rotor blades,
  - (d) and an air filled, annular cushion disposed be-

tween the said shoulders of said lateral extensions and said rotor blades to permit adjustable movement of said blades relative to the horizontal as well as in the plane of rotation of the blades.

3. The logging apparatus of claim 1 wherein
  - (a) said aircraft has an upstanding post for said rotor blades having a lateral extension for each of said blades,
  - (b) an overlapping connection between said extensions and their respective rotor blades,
  - (c) vertical shoulder means on the ends of each of the overlapping ends of said lateral extensions and said rotor blades,
  - (d) and an air filled annular cushion disposed between the said shoulders of said lateral extensions and said rotor blades to permit flexing movement of said blades relative to said extensions,
  - (e) and means connected between adjacent ones of said blades to anchor the latter against rotation on their longitudinal axes.
4. The logging apparatus of claim 1 wherein
  - (a) said rotor blades have an internal longitudinal passageway,
  - (b) an upstanding hollow post on said aircraft supporting said blades and having its interior in communication with the passageways in said blades,
  - (c) means defining outlet jet apertures from said passageways adjacent to the outer ends of said blades arranged to impart a rotative force to said rotor upon the ejection of forced air from said apertures,
  - (d) air scoop means on said aircraft to catch air from said propeller,
  - (e) and means establishing communication between said air scoop means and the interior of said post whereby forced air from said propeller is directed to said jet apertures.
5. The logging apparatus of claim 1 including
  - (a) an upstanding post on said aircraft having a lateral extension for each of said blades,
  - (b) an overlapping connection between said extensions and their respective rotor blades,
  - (c) an air filled, annular cushion disposed between the overlapping portions of each of said lateral extensions and said rotor blades to permit flexing movement of said blades relative to said extensions,
  - (d) an arm pivotally connected at one of its ends to one of said rotor blades,
  - (e) and means defining a socket in another of said rotor blades which is adjacent said one of said rotor blades,
  - (f) said socket means slidably receiving the other end of said arm,
  - (g) said arm and socket means being arranged to anchor said rotor blades against rotation on their longitudinal axes on their respective lateral extensions.
